(57) **CLAIM**

The ornamental design for a boat for use in a material deposition apparatus, as shown and described.

DESCRIPTION

FIG. 1 is a perspective view of a boat for use in a material deposition apparatus showing our new design;

FIG. 2 is a top plan view thereof;

FIG. 3 is a side view thereof;

FIG. 4 is another side view thereof;

FIG. 5 is another side view thereof;

FIG. 6 is another side view thereof;

FIG. 7 is a bottom view thereof;

FIG. 8 is a perspective view thereof shown in a used condition, with a cup partially removed from the carriage;

FIG. 9 is another perspective view thereof in a used condition, with a cup completely removed from the carriage;

FIG. 10 is a top plan view of FIG. 9;

FIG. 11 is a perspective view of the removed cup in FIG. 8, shown separately for ease of illustration;

FIG. 12 is a top plan view of FIG. 11;

FIG. 13 is a side view of FIG. 11; and,

FIG. 14 is a bottom view of FIG. 11.

Broken lines are used in the drawings to illustrate environment. The features illustrated in broken lines form no part of the claimed design.
